US00D646440S

(12) **United States Design Patent**
Chance et al.

(10) **Patent No.:** US D646,440 S
(45) **Date of Patent:** ** Oct. 4, 2011

(54) **PET FEEDER**

(75) Inventors: **Christopher E. Chance**, Bella Vista, AR (US); **Andrew Bojie**, Centerton, AR (US)

(73) Assignee: **Stout Stuff, LLC**, Bentonville, AR (US)

(**) Term: **14 Years**

(21) Appl. No.: **29/385,843**

(22) Filed: **Feb. 21, 2011**

(51) **LOC (9) Cl.** 30-03

(52) **U.S. Cl.** D30/133; D30/130; D30/131

(58) **Field of Classification Search** D30/133, D30/121, 128, 130, 132; 119/52.1, 55, 61.5–61.56; D6/480–485; 248/188; 312/204; 108/153.1–157
